Electro Products Corp., Brooklyn, N.Y.

Filed Aug. 13, 1973, Ser. No. 388,332

Term of patent 14 years

Int. Cl. D14—03

U.S. Cl. D26—14 G

FIG.1

FIG.2

FIG. 1 is a perspective view of a horn speaker showing my new design; and

FIG. 2 is a top plan view, partially broken away and in section, illustrating the angled arrangement of the horn speakers.

The undisclosed side is a mirror image of the side shown and the rear is plane and unornamented.

The characteristic feature of the design resides in the horn speakers embodied in the upper portion of the enclosure shown in the drawing.

I claim:

The ornamental design for a horn speaker, as shown and described.
